CLAIM

The ornamental design for a charging device, as shown and described.

DESCRIPTION

FIG. 1 is a front perspective view of a charging device showing my new design.

FIG. 2 is a bottom view of the charging device thereof.

FIG. 3 is a top view of the charging device thereof.

FIG. 4 is a front view of the charging device thereof. The rear view of the charging device thereof is a mirror image of the front view.

FIG. 5 is a right side view of the charging device thereof. The left side view of the charging device thereof is a mirror image of the right side view.

FIG. 6 is another front perspective view of the charging device thereof, shown in use; and,

FIG. 7 is another front perspective view of the charging device thereof, shown in use.

The broken lines shown represent unclaimed subject matter and form no part of the claimed design.

1 Claim, 5 Drawing Sheets
